UNITED STATES PATENT OFFICE.

LOUIS T. WEISS, OF BROOKLYN, NEW YORK, ASSIGNEE TO ANTONIN CHAPAL, OF BROOKLYN, NEW YORK.

FLESHING-MACHINE.

1,278,804.

Specification of Letters Patent. Patented Sept. 10, 1918.

Application filed July 10, 1917. Serial No. 179,603.

To all whom it may concern:

Be it known that I, LOUIS T. WEISS, a citizen of the United States, and residing in the borough of Brooklyn of the city of New York, county of Kings, in the State of New York, have invented certain new and useful Improvements in Flesching-Machines, of which the following is a specification, reference being had to the accompanying drawings, forming a part hereof.

This invention has for its object to produce an improved machine for flesching hides or skins, which shall afford greater facility in its use, particularly in respect to the grinding of the knife, the adjustment of the guards with relation to the knife and general operation of the machine, than machines of like character heretofore used. The invention will be more fully explained herein-after with reference to the accompanying drawings, in which it is illustrated and in which:

Figure 1 is a view of the improved machine in side elevation, the floor upon which it stands being indicated in section.

Fig. 2 is a partial view of the same in vertical section on the plane indicated by the line 2—2 of Fig. 1, looking in the direction of the arrows, the scale of this figure 30 being larger than that of Fig. 1.

Fig. 3 is a partial view in elevation as seen from the opposite side to that represented in Fig. 1, but on a larger scale.

Fig. 4 is a top view, partly in section, on the plane indicated by the line 4—4 of Fig. 3.

In the machine shown in the drawings the working parts are supported upon a suitable standard *a* which can be secured to the floor, such standard forming also a guard for the driving belt *b* which receives its motion from a driving pulley *c* and countershaft *c'* supported below the floor. To the upper part of the standard *a* is bolted a split tube *d* which is provided with a clamping screw *d'* and with bearings for a shaft *e* which carries a pinion *e'* and a hand-wheel *e''*. The working head of the machine is carried by a vertical shaft *f* which telescopes within the split tube *d* and is formed or provided with a vertical rack *f'* for engagement by the pinion *e'* so that the working head can be raised and lowered to take up the slack of the driving belt *b* or to give it slack for the purpose of stopping the

flesching knife. The clamping screw *d'* 55 tightens the split tube *d* about the shaft *f* so as to retain the head in adjusted position.

The working head comprises a frame, a flesching knife with its driving pulley suitably mounted in the frame, and suitable 60 guards. The frame *g* secured upon the upper end of the vertical shaft *f*, has mounted therein on suitable bearings, a driving pulley *h* which preferably has formed therewith an extended wedge *h'*, to which is secured, as 65 by screws *h''*, the flesching knife, *k*. This knife is preferably formed as a flat disk, with a knife-flange *k''*, flared outwardly at an angle somewhat greater than 90° with respect to the body of the disk, so that the 70 necessary sharp edge may be maintained by grinding only upon the outer surface. In this way the knife can be kept sharp easily by the application of a suitable abrading tool which may be held in the hand and 75 without requiring the complicated arrangements necessary to be employed when the knife must be ground on the inner surface and always difficult of proper adjustment.

As the operator stands in the working position, facing the working head, his body is protected from contact with the knife by a shield *m*, which is preferably concave, as shown, and is hinged to the top of the frame *g*, as shown at *m'*, so that the shield can 80 be thrown upward out of the way when it is necessary to get at the knife for purposes of sharpening. The shield is provided with a slotted arm *m''* which co-operates with a clamping bolt *m'''* by which the shield is 85 held in adjusted working position.

On the right hand side of the head, as the operator stands facing the machine, is secured adjustably, by means of clamping bolts *n'* and slots *n''*, a guard *n* formed to 95 overlap the knife, as clearly shown in Fig. 4, and curved to conform generally to the curvature of the knife, as shown in Fig. 3, and provided with parallel arms *n''* in which are formed the slots *n'''*, the two arms 100 being united at the ends opposite the guard by a cross-bar *n'''* to give rigidity.

On the left hand side of the frame, as the operator stands facing the machine, is a flat guard plate *o* which is curved to conform generally to the curvature of the knife and is supported by parallel arms *o'* united 105 at the opposite ends by a cross-bar *o''* and

slotted as at ϕ^3 for coöperation with clamping bolts ϕ^4 . By the described arrangements the two guard plates n and o can be adjusted readily with respect to the edge of the 5 knife, according to the character of the work being done.

It will be understood that in the operation 10 of the machine the hide or skin to be fleshed, as indicated by broken lines in Fig. 4, is drawn across the edge of the fleshing knife as it is exposed between the guards n and o and while it is rotating at high speed, and the flesh adhering to the inner 15 side of the skin or hide is thereby quickly removed.

I claim as my invention:

In a fleshing machine, having a supporting frame and a rotary fleshing knife mounted therein to rotate on a horizontal axis, a shield mounted upon the frame so that it 20 can be turned up to give access to the knife, and forming normally a rest and shield for the body of the operator, the shield being formed with a slotted projecting member and the frame being provided with a clamp- 25 ing bolt to coöperate therewith.

This specification signed his 6th day of July, A. D. 1917.

LOUIS T. WEISS.
